PUMPING JACK

Joseph R. Mahan, Toledo, Ohio, assignor to The
National-Superior Company, Toledo, Ohio, a
corporation of Delaware

Application March 12, 1932, Serial No. 598,401

9 Claims. (CL. 74—41)

My invention relates to a pumping jack designed particularly for oil wells, but adaptable to other apparatus.

The principal object of this invention is to provide a pumping jack with a supporting frame constructed to withstand severe usage. Another object is to provide for a walking beam a mounting which is adjustable to position the pump rod in alignment with the well hole or pump barrel after the frame has been set upon its foundation.

Referring to the accompanying drawing, Fig. 1 is a side elevation of a pumping jack containing my invention; Fig. 2, an end elevation of Fig. 1; Fig. 3, a plan view of a modification and showing the bearings, the trunnion, and the swivel plate T-bar, shown on an enlarged scale, the walking beam and its supporting frame being omitted; Fig. 4, a side elevation of Fig. 3, a portion being in section on the line 4—4 on Fig. 3; and Fig. 5, a plan view of the swivel plate T-bar.

Referring to the drawing, 1 designates horizontal base members spaced apart by the bolts 2. The inclined members 3 are attached to the extreme ends of the horizontal members 1 and in the same plane thereof. The members 3 converge upwardly, forming with the horizontal members 1 triangular frames to which are fastened the vertical web portions of the T-bars 4. The vertical members 5 are attached at their lower ends to the center of the horizontal members 1 and at their lower ends to the center of the horizontal members 1 and at their upper ends to the vertical web portions of the T-bars 4 between the converging members 3. The members 5 thus bisect the triangular frames made up of the members 1 and 3. 6 represents horizontal base members extending outwardly from the center of the horizontal members 1, terminating at the base of the inclined brace members 7 which converge toward the top of the triangular frames and are fastened to the vertical members 5 by means of the plates 8. Thus there is provided a pair of trihedral supporting frames having clearance between them and forming a portable unitary structure.

9 represents bearing housings which are supported on the horizontal flanges of the T-bars 4 and are clamped thereto by the bolts 10 which pass through the horizontal flanges 14 of the housing 9 and thence through the enlarged holes 11 in the horizontal flanges on the T-bars 4.

12 indicates bosses or blocks fastened on the opposite ends of the horizontal flanges of the T-bars 4. These bosses are drilled and tapped horizontally to receive the adjusting bolts 13 which 55 abut the flanges 14 of the housing 9 and may be

locked against the faces of the bosses by the lock nuts 15.

16 designates a horizontal shaft or trunnion supported by the bearing 9. The plate 17 carried by the trunnion 16 is bolted to the walking beam 18 near or about its center. The walking beam 18 is provided with the pendent member 19 and a diagonal member 20 which are connected together to form a triangular frame. The lower portion of the member 19 has attached thereto the pull rod 10 21 designed to be connected to a suitable reciprocating power device for causing vertical oscillation of the walking beam 18 on the shaft 16.

22 designates the upper portion of the pump barrel containing the pump rod 23 which is suspended by the links 24 that are in turn supported by the bearing 25 at one end of the walking beam 18.

The bearings 9, as shown in Fig. 2, are separate or individual castings, each resting on its respective T-bar member 4 and held in spaced-apart relation by the spacing bolt 26.

Figs. 3 and 4 show the bearings 9' which are connected together by the web 27, the bearing structure being in one piece. When the one-piece 25 bearings are used, the spacing bolt 26 is not necessary to space the supporting triangular frames at their apex as the web 27 is sufficient to maintain a rigid structure when this bearing structure 9' is clamped to the T-bars 4.

In order to accurately align the pump rod 23 coaxially with the pump barrel 22 after the pump jack supporting frame has been fixed to its foundation, the bearing clamping bolts 18 are loosened and the four adjusting bolts 13 are turned in their tapped holes in the bosses 12 so that they bear against the bearing flanges 14 and impart to the bearing structure and walking beam longitudinal or arcuate motion, or both, thus obtaining micrometer adjustment of the walking beam, enabling the one making the adjustment to accurately align the pump rod coaxially with the pump barrel 22. By tightening the bolts 10 the bearing structure may be clamped to the T-bars 4 and the adjusting bolts 13 may be locked in position by the lock nuts 15, thus decreasing the possibility of the pump rod getting out of alignment with the pump barrel.

I claim:—

1. In a pumping jack for supporting a walking beam to operate an element suspended in a well, the combination with trunnions extending from either side of the beam, of a pair of supporting frames positioned at either side of the vertical plane in which the beam is to swing, bearings to

receive said trunnions and movably mounted on said supports, and screw threaded means to adjust the bearings relative to the supports to center the element in the well.

5. 2. In a pumping jack for supporting a walking beam to operate an element suspended in a well, the combination of a pair of trihedral supporting frames positioned at either side of the vertical plane in which the beam is to swing, bearings 10 to receive the trunnions and mounted on the frames, and screw threaded means to adjust the bearings relative to said frames to center the element in the well.

15. 3. In a pumping jack for supporting a walking beam to operate an element suspended in a well, the combination with trunnions extending from either side of the beam, of a pair of supporting frames positioned at either side of the vertical plane in which the beam is to swing, bearings to 20 receive said trunnions and mounted on said supports, and abutment bolts to adjust the bearings relative to the supports to center the element in the well.

25. 4. A retractible walking-beam structure of the character described, including: a Samson post; a walking-beam; means for pivotally securing said walking-beam to the upper part of said Samson post, said securing means being movable relative to the upper end of said Samson post in a horizontal direction; and means connected to said Samson post operative to exert a force to move 30 said securing means horizontally relative to the upper end of said Samson post.

35. 5. In a pumping machine, the combination with a vertical support, of a bearing member mounted on said support and movable horizontally thereon, a walking beam mounted on said bearing member and arranged to swing on a horizontal axis, and means carried by said support and arranged to 40 engage said bearing member to move the latter

relative to said support and thus adjust the walking beam to properly center it in operative position.

6. A bearing support for Samson posts comprising a horizontal bearing plate connected rigidly with the post, a supporting plate adjustably mounted on the bearing plate and acting to support a rocker bearing, and means for shifting the supporting plate longitudinally in opposite directions, the same means also constituting means for adjusting the supporting plate arcuately. 5

7. A bearing support for Samson posts comprising a horizontal bearing plate connected rigidly with the post, a supporting plate adjustably mounted on the bearing plate and acting 15 to support a rocker bearing, means for shifting the supporting plate longitudinally in opposite directions, the said means also constituting means for adjusting the supporting plate arcuately, and means for locking the supporting plate against 20 movement.

8. A bearing support for Samson posts comprising a horizontal bearing surface in fixed relation with the post, a rocker bearing unit adjustably mounted on the bearing surface, and screw means 25 for shifting the bearing unit longitudinally in opposite directions, the said means also constituting means for adjusting the bearing unit arcuately.

9. A bearing support for Samson posts comprising a horizontal bearing surface in fixed relation with the post, a rocker bearing unit adjustably mounted on the bearing surface, screw means for shifting the bearing unit longitudinally in opposite directions, the said means also constituting 35 means for adjusting the bearing unit arcuately, and means for locking the rocker bearing unit against movement. 30
